CAR DOOR

Carl E. Eklind, Chicago, Ill., assignor to The Youngstown Steel Door Company, Cleveland, Ohio, a corporation of Ohio

Application April 5, 1938, Serial No. 200,135

8 Claims. (Cl. 189—46)

This invention relates to car doors and is concerned more particularly with insulated swinging doors for railway refrigerator cars.

It is an object of this invention to provide refrigerator car doors which shall be of reduced thickness and so constructed that requisite strength and insulating value are maintained.

A further object is to provide refrigerator car doors embodying outer corrugated metallic panels whereby doors of reduced thickness together with sufficient strength and insulating properties may be secured.

A further object is to provide refrigerator car doors of reduced thickness carrying locking and operating mechanism on the outside wherein said mechanism shall lie inwardly of the outer plane of the car walls.

A further object is to provide refrigerator car doors of reduced thickness, requisite strength and insulating value and which shall be lighter in weight than known refrigerator car doors.

A further object is to provide refrigerator car doors having metallic frames to which wooden stiles and rails are adapted to be secured and outer corrugated metallic panels whose corrugations increase in width and depth in the direction of the hinged edges of the doors.

A further object is to provide refrigerator car doors having metallic frames to which wooden stiles and rails are adapted to be secured and outer corrugated metallic panels overlapping and secured to the outer face of the vertical members of the frames and reinforced by stiffener plates secured to the inner face of the panels and the lateral faces of the vertical members of the metallic frames.

Other objects of the invention will become clear as the description thereof proceeds.

In the drawings forming part of this specification:

Figure 1 is an elevation of a portion of a refrigerator car showing swinging doors embodying the invention.

Figure 2 is a horizontal section taken on line 2—2 of Figure 1.

Figure 3 is a vertical section taken on line 3—3 of Figure 1.

Figure 4 is a vertical section taken on line 4—4 of Figure 1.

Figure 5 is a plan view of a combined threshold plate and keeper.

Figure 6 is an elevation of the threshold plate of Figure 5.

Figure 7 is a vertical section taken on line 7—7 of Figure 6.

Figure 8 is a vertical section taken on line 8—8 of Figure 6.

Figure 9 is a view similar to Figure 3 showing a modified form of sealing strip.

Figure 10 is a detailed elevation showing means for holding the overlapped door in open position.

In the drawings which illustrate a preferred embodiment of the invention the numeral 10 designates the side wall of a refrigerator car. This wall as more clearly shown in Figure 2 of the drawings may comprise outer metallic sheathing 11 secured to inwardly extending posts. The door posts are indicated at 12—12. Abutting these posts is the fibrous covering 13. The inner wooden lining of the wall 10 is shown at 14 and between the fibrous member 13 and the inner wooden lining, insulating material 15 is disposed. Within the angle formed by the flange 16 and web 17 of the door posts the wooden nailing strips 18—18 are seated. The construction of the refrigerator car wall hereinabove described is of well known construction and as such forms no part of the instant invention except as hereinafter indicated.

The door posts 12—12 in conjunction with a header 19 and threshold plate 20 define a door opening in the car wall 10 which is adapted to be closed preferably by the swinging overlapping doors 21 and 22. The overlapped door 21 comprises a metallic frame substantially rectangular in shape. This frame is formed by the vertical member 23 arranged with its flange 24 parallel to the car wall 10 and its flange 25 extending inwardly therefrom at right angles to the car wall. The other vertical member 26 of the metallic frame is substantially Z-shaped in section and is arranged with its web 27 at right angles to the wall of the car and its flanges 28 and 29 parallel thereto. The flange 29 is offset inwardly as indicated at 30 for a reason which will later appear. The upper and lower horizontal members 31 and 32 of the metallic frame are angular in cross section, the flanges 33 and 34 being arranged vertically and the flanges 35 and 36 extending horizontally inwardly.

It will be observed from Figures 2 and 3 of the drawings that the vertical frame member 23 to which the hinges mounting the door upon the car wall are secured extends outwardly relative to the remaining frame members and lies substantially flush with the outer plane of the car wall. A reinforcing metallic covering panel 37 is secured to the flanges of the metallic frame members which lie substantially parallel to the wall of the car. The main portion of the metallic panel 37 is also inset relative to the outer plane

of the car wall as clearly shown in Figure 2 of the drawings. Adjacent the vertical frame member 23 the metallic panel is offset outwardly as indicated at 38 and extended into overlapping engagement with the flange 24 of the frame member 23 to which it is secured as by means of rivets 39. The metallic panel 37 is stiffened by means of a plurality of horizontal corrugations 40 which as clearly appears from Figures 1 and 2 of the drawings increase in width and depth as they approach the offset portion 38 of the panel. Moreover, as shown in Figure 2 of the drawings the horizontal corrugations 40 merge into said offset portion of the metallic panel. Additional stiffness is imparted by means of stiffener plates 41 disposed in the space between the offset portion of the panel and the flange 25 of the vertical frame member 23 and preferably welded to the panel and the flange. Additional stiffness is secured by means of wooden blocks 42 and 43 disposed within the space above defined at the upper and lower edges of the door.

A wooden nailing board 44 is seated within the re-entrant angle formed by the flanges 24 and 25 of the frame member 23. Similarly, a wooden nailing board 45 is seated within the re-entrant angle formed by the web 27 and outturned flange 28 of the substantially Z-shaped frame member 26. These nailing boards are fastened to the frame members by means of bolts in the customary manner.

The metallic frame members in conjunction with the outer metallic covering panel provide a pocket 46 adapted for the reception of insulating material. The insulating material may be pre-formed and inserted as a unit within the pocket and is of at least the same insulating value as the insulation employed in the car wall 10. Preferably the insulation used in the door 21 comprises a plurality of strips of aluminum foil 47 secured between fibrous boards 48. The pocket 46 is closed and the insulation retained therein by means of a plywood panel 49 extending in across the pocket and fastened to the nailing boards 44 and 45. The plywood panel used in place of the customary tongue and groove boards lends stiffness to the door.

The plywood panel, moreover, together with the metallic covering panel 37 and the frame members 35 and 36 form pockets in the upper and lower portions of the door within which the nailing boards 50 and 51 are secured.

The construction of the overlapping door 22 is the same as the construction of the overlapped door 21 except as noted below. In place of the front vertical Z member 27 of the metallic frame of the door 21 a front vertical angle 53 is utilized. This member is arranged with its flange 54 abutting the inside of the metallic covering panel 52 and extending to the vertical edge of said panel. The other flange 55 of the vertical frame member 53 extends inwardly at right angles to the wall of the car. A nailing board 56 is seated within the re-entrant angle formed by the flanges of the member 53.

The doors 21 and 22 as hereinabove indicated are overlapped. The metallic panel of the door 22 together with the flange 54 of the vertical frame member 53 are extended outwardly beyond the board 56 as clearly shown in Figure 2 of the drawings so as to have overlapping engagement with the nailing board 45 carried at the front vertical margin of the door 21. The vertical margin of the door 22 is disposed within the offset 30 formed in the flange 29 of the Z frame mem-

ber 27 so that the two doors are substantially flush when in closed position. By thus overlapping the two doors weather is excluded. The weather tight quality of the two doors in their meeting edges is, moreover, enhanced by the inclined point between the boards 45 and 56 which is disposed in offset relationship to the outer edge of the door 22. Further tightness against the ingress of the elements is obtained by means of a sponge rubber sealing strip 57 which is angular in section and disposed within a correspondingly shaped recess 58 formed in the board 45. The sealing strip 57 is retained within the recess by means of a canvas covering strip 59.

Sealing of the upper margin of the door may be obtained by means of the spring pressed wooden board 60 seated within a correspondingly formed recess 61 of the wooden header 19 and the sealing strip 62 against which the board 60 bears. The sealing strip 62 is retained in position by means of a canvas strip 63 nailed to the header.

The bottom edge of the door is sealed by means of a fibrous board 64 seated within a recess 65 formed in the threshold plate 20 hereinafter explained in greater detail. In addition, the lower edge of the door is sealed by means of a sponge rubber strip 66 fastened to the inner face of the nailing board 51 and adapted to bear against a metallic member 67 which covers the edge of the flooring of the car as appears from Figure 4 of the drawings.

From the foregoing, it will be apparent that a strong door, lighter in weight than the presently known refrigerator car doors is produced and in addition, there is secured a door whose insulating qualities are not decreased while at the same time the thickness of the main portion of the door is reduced. By reason of the reduction in the thickness of the door, the operating and locking mechanism 68 is disposed upon the outside of the doors and within the outer plane of the car wall as more clearly indicated in Figures 2, 3, and 4 of the drawings. The operating and locking mechanism is of well known construction and embodies a vertical bar 69 rotatably carried upon the outside of the overlapping door 22 by means of the upper and lower brackets 70 and 71 and the intermediate bracket 72. A lever 73 is utilized to impart rotation to the bar. Cranks 74 and 75 are secured to the upper and lower ends respectively of the bar 69 and are adapted to cooperate with the upper and lower keepers 76 and 77 carried respectively by the header 19 and the threshold plate 20.

The doors 21 and 22 are hinged to the door posts 12 by means of a plurality of hinges 78 so disposed that only the knuckles and hinged pins of the hinges are located outwardly of the car wall.

The inner vertical edges of the doors 21 and 22 are sealed by means of sponge rubber strips 79 fastened to the nailing boards 18 by canvas strips and adapted to be pressed into recesses 80 formed in the nailing boards 44 by means of the spring pressed wooden strips 81.

In Figure 9 of the drawings a sponge rubber sealing strip 82 may be used to seal the upper edge of the door in place of the members 60, 61 and 62 as shown in Figure 3 of the drawings.

In Figures 5 to 8 inclusive of the drawings the structure of the threshold plate is illustrated in greater detail. As shown the threshold plate is in the form of a casting provided with the recess 65 within which the fibrous board 64 is re-

ceived. The keeper 77 is formed integrally with the threshold plate. Attaching ears 83 are formed at the ends of the threshold plate by means of which said plate is secured to the door posts 12-12. In addition the vertical flange 84 of the threshold plate is provided with a downwardly extending vertical flange 85 spaced inwardly of the inner face of the inner flange 84. The flanges 84 and 85 provide a pocket 86 within which the upstanding vertical flange 87 of the side sill angle 88 is adapted to be received. In this fashion the side sill angle is utilized to strengthen the threshold plate.

In Figure 10 of the drawings there is illustrated a device fastened to the outer face of the door 21 which provides an auxiliary locking means for the door in closed position and means for locking the door in open position. This device comprises a locking bolt 89 slidably retained within a housing member 90 fastened to the door as by means of rivets 91. The locking bolt 89 is provided with a hook 92 at its lower end and when in open position this hook is adapted to engage and automatically lock behind a detent 93 carried by the member 94 fastened to the car wall 10.

It will be clear from the foregoing that the door of the instant invention is characterized by lightness, reduction in thickness, strength and proper insulating quality. The operating and locking mechanism for the doors is inset inwardly relative to the outer plane of the car wall thereby eliminating the danger of destruction of this mechanism as a result of sideswiping of the cars. This disposition of the operating and locking mechanism and lightness of the doors is obtained without detracting from strength and insulating value.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. An insulated door for refrigerator cars comprising a metallic frame embodying vertical and horizontal members, one of said vertical members extending outwardly beyond the remaining members, a metallic panel secured to said frame and forming a pocket therewith, said panel lying inwardly of and being offset outwardly in laterally spaced relation to said one vertical member for securing to the outer face thereof, stiffening members disposed between and secured to said panel offset and said one vertical member, wooden members fastened to said metallic frame, insulation in said pocket and a wooden panel fastened to said wooden members and closing said pocket.

2. An insulated door for refrigerator cars comprising a metallic frame embodying vertical and horizontal members, one of said vertical members extending outwardly beyond the remaining members, a metallic panel secured to said frame and forming a pocket therewith, said panel lying inwardly of and being offset outwardly in laterally spaced relation to said one vertical member for securing to the outer face thereof, stiffening members disposed between and secured to said panel offset and said one vertical member, wooden members fastened to said metallic frame, insulation in said pocket and a wooden panel fastened to said wooden members and closing said pocket, said metallic panel being formed with a

plurality of spaced horizontal corrugations increasing in width and depth toward said one vertical member and merging into said panel offset.

5 3. As an article of manufacture a composite metallic frame and metallic panel for a refrigerator car door, said frame comprising angular, horizontal and vertical members arranged in rectangular form, one of said vertical members extending outwardly beyond the remaining members of said frame, said metallic panel being secured to the outside of said remaining frame members and being offset outwardly adjacent to said one vertical frame member and overlapped upon and secured to the outside thereof, said frame being adapted to receive wooden members and said panel and frame forming a pocket for the reception of insulating material.

20 4. As an article of manufacture a composite metallic frame and metallic panel for a refrigerator car door, said frame comprising angular, horizontal and vertical members arranged in rectangular form, one of said vertical members extending outwardly beyond the remaining members of said frame, said metallic panel being secured to the outside of said remaining frame members and being offset outwardly adjacent to said one vertical frame member and overlapped upon and secured to the outside thereof, said frame being adapted to receive wooden members and said panel and frame forming a pocket for the reception of insulating material, said metallic panel having spaced horizontal corrugations merging into said panel offset.

25 5. As an article of manufacture a composite metallic frame and metallic panel for a refrigerator car door, said frame comprising angular, horizontal and vertical members arranged in rectangular form, one of said vertical members extending outwardly beyond the remaining members of said frame, said metallic panel being secured to the outside of said remaining frame members and being offset outwardly adjacent to said one vertical frame member and overlapped upon and secured to the outside thereof, said frame being adapted to receive wooden members and said panel and frame forming a pocket for the reception of insulating material, and stiffening plates interposed between and welded to said panel offset and said one vertical frame member.

30 40 6. In a refrigerator car having an insulated wall provided with a door opening, a pair of overlapping insulated doors having bevelled meeting edges hinged to said wall in said door opening, resilient sealing material secured to the outside and the bevelled edge of the overlapped door, the overlapping door having an outer portion extending beyond the bevelled edge thereof, said outer portion and said bevelled edge of said overlapping door engaging respectively the sealing material secured to the outside and bevelled edge of the overlapped door, said outer portion engaging the overlapped door beyond the sealing material whereby a triple seal is formed.

45 55 7. An insulated door for refrigerator cars comprising metallic stiles, upper and lower metallic rails secured to said stiles and a metallic panel, one of said stiles extending outwardly beyond the other stile and said rails, said panel being secured to said stiles and rails and being offset inwardly relative to said one stile, said panel, stiles and rails forming an inwardly opening pocket for the reception of insulation, wooden members secured to said stiles and rails, insulation disposed in said pocket and a wooden panel

fastened to said wooden members and closing said pocket.

8. As an article of manufacture a composite metallic frame for a refrigerator car door, said frame comprising angular metallic stiles and upper and lower angular metallic rails secured to said stiles, one of said stiles extending beyond

the other stile and said rails, said metallic panel being secured to said stiles and rails and being offset inwardly relative to said one stile, said frame being adapted to receive wooden members, said panel and frame forming a pocket for the reception of insulating material.

CARL E. EKLIND.
